CLAIM

The ornamental design for a keyboard with trackball pointing device, as shown and described.

DESCRIPTION

FIG. 1 is a top front left side perspective view of the keyboard with trackball pointing device showing our new design the broken lines being shown for illustrative purposes only and form no part of the claimed design; and, FIG. 2 is an enlarged fragmentary top view thereof. The undisclosed right side view is identical to the left side and the bottom and rear views are unornamented.
